CATCH-CORD ELIMINATOR

Application filed April 5, 1929. Serial No. 352,879.

Our invention relates to devices carried by loom temples for dispensing with the use in weaving of the catch cord or selvage cord formerly necessarily employed to retain the filling, and sometimes styled catch cord 5 eliminators.

The essential objects of our invention are to enable the device to be employed either upon right hand or left hand temples; to enable adjustment of the device longitudinally of the loom to accommodate cloth of various widths; to insure invariable engagement of the needle with the shuttle-thread whereby missing any pick is avoided; to maintain the 15 cloth at its natural width throughout the operation; to facilitate the application and removal of the device to and from the temple; and to attain these ends in a simple, inexpensive and easily operable structure.

20 To the above ends primarily our invention consists in such parts and in such combinations of parts as fall within the scope of the appended claims.

In the accompanying drawings which form 25 a part of this specification

Figure 1 is a perspective view, from a point above and in front, of our eliminator applied to a loom-temple,

Figure 2, a fragmentary perspective of the 30 base plate and bearing block,

Figure 3, an isometric view of the base plate and a part of the bearing block,

Figure 4, a detailed view of a part of the bearing block detached, and

35 Figure 5, a detailed view of the rocking member.

Like reference characters indicate like parts throughout the views.

Our device is herein shown supported by 40 a loom-temple 10 of well known construction comprising the body 11 attachable to the top of a breast beam by the retaining plate 12, and a slide including the forwardly directed 45 slidable arm portion 14 and the usual selvage retaining box portion. The latter consists of a base 16 and top 17, clamped together by a screw or bolt 19 whose shank, not shown, passes through an oblong longitudinally disposed slot 22 in an attaching or base plate 23 50 which is thereby fixed to the upper face of

the selvage retaining box, and, by virtue of the slot, is adjustable longitudinally thereof. In this case a washer 24 is interposed between the plate 23 and the head of the screw 19. Integral with an intermediate portion of the plate 23 is a lateral forwardly projecting upwardly inclined lug or guide arm 26 provided near its free end with an eye 27.

Cast with the plate 23 or fixed thereto in any convenient manner transversely thereof 55 is a bearing block 29 adjacent the arm 26 and parallel thereto. Journaled in a bearing opening 30 in the forward portion of the block is a rock shaft 32. In order to facilitate the complete removal of the rock shaft from the block if desired, the block is divided, as at 34, into a seat section 35 and a superposed detachable rectangular section 36. The bearing opening 30 is formed by registering semicircular bores 38 and 39 in the seat section 35 60 and in the lower face of the removable section 36. The latter section is secured by a screw 40 passing through a vertical hole 41 therein, and entering a threaded cavity 42 in the block seat section 35.

75 Integral with one end of the rock shaft 32 a forwardly directed lever arm 44, disposed at right angles to the shaft, has a finger 47 integral with its end and right angularly disposed thereto, the arm and finger forming a 70 crank. Integral with the other end of the shaft 32 is a forwardly directed downwardly inclined stop arm 49 disposed rectangularly with relation to the shaft, and at a radial angle of less than 90 degrees to the arm 44. 75 Integral with the forward end of the arm 49 is an upwardly directed contact lever 50 inclined at an acute angle to the latter.

80 A thread engaging member is in this instance bent up from a length of wire whose upper end is formed into a series of coils or a sleeve 53 disposed at right angles to the remainder of the wire length which constitutes an integral pointed needle 54. The sleeve 53 is loose on the finger 47, and the needle 54 85 passes downwardly and loosely through the eye 27 of the lug 26.

The arm 49, whose outer end forms a stop, is normally pressed downwardly in contact with the front portion of the plate 23 by the 100

following means. A horizontal rod 56 is frictionally or otherwise held in a transverse bore 57 in the rear portion of the block 29. A resilient length of wire is coiled helically upon the rod 56 to form a spring sleeve 59, one of whose ends 60 is fixed in a hole 61 in the outer end of the rod, while, at the other end of the coil, the wire is extended to form a spring arm 62 terminating in a loop 63 engaging and depressing the arm 49.

10 The operation of our device is as follows: As the loom lay in its vibration swings towards the beam, the lay, or an abutment carried thereby, will strike and rearwardly push the lever 50 to the position shown in broken lines in Figure 1, thereby raising the point of the needle 54 above the plane of the fabric being woven, since it is essential that the needle be out of the way while the thread laid in the shed by the shuttle is being beat up by the loom reed. When, however, the loom lay returns to permit the shuttle to be thrown, and a new shed to be formed therefor, the needle 54 will have been downwardly impelled into the path of the shuttle thread 65 by the spring 59, thus retaining the thread against the pull of the shuttle as it progresses through the succeeding shed. Excessive descent of the needle is prevented by contact 20 of the stop arm 49 with the plate 23.

25 It is to be understood that the invention is not limited to the specific form herein illustrated and described, but may be embodied in other forms without departure 30 from its spirit as defined by the following claims.

We claim:—

1. In a device of the type set forth, a loom temple slide, a plate upon the slide, a rock shaft pivotally supported upon the plate, a forwardly directed crank upon the shaft, a downwardly directed needle upon the crank, a needle guide on said plate and an upwardly directed contact lever carried by the shaft.
- 40 2. In a device of the type set forth a loom temple slide, a plate upon the slide, a lateral guide arm upon the plate provided with an eye, a rock shaft disposed at right angles to the arm pivotally supported upon the plate, a crank upon the shaft, a needle upon the crank slidable through the eye, an upwardly directed contact lever supported by the shaft, and resilient means for actuating the rock shaft.
- 45 3. In a device of the type set forth, a loom temple slide, a plate upon the slide, a forwardly projecting guide arm upon the plate provided with an eye, a bearing block upon the plate, a rock shaft mounted in the block; a crank upon one end of the shaft, a depending needle pivotally supported upon the crank slidable through the eye, an upwardly directed contact lever, a forwardly directed 50 stop arm engageable with the plate joining

the shaft with the lever, and spring means for pressing the stop arm against the plate.

4. In a device of the type set forth, a loom temple slide, an attaching plate upon the slide provided with an oblong longitudinal slot, a clamping screw in the slide engaging the plate through the slot, a forwardly directed lateral guide arm upon the plate provided with an eye, a bearing block upon the plate adjacent the slot, a rock shaft journaled in the block, a crank upon the shaft, a depending needle upon the crank extending loosely through the eye, an upwardly directed contact lever rigid with the shaft, and resilient means for yieldingly holding the lever.

5. In a device of the type set forth, a loom temple slide, a plate upon the slide, a bearing block upon the plate, a rock shaft mounted in the block, a crank comprising a forwardly directed lever arm upon one end of the shaft, and a finger parallel with the shaft upon the free end of the arm, a downwardly directed needle upon the finger, a forwardly directed stop arm upon the other end of the shaft disposed at a radial angle to the lever arm adapted to engage the plate when the needle descends, and an upwardly directed contact lever upon the stop arm.

6. In a device of the type set forth, a loom temple slide, a plate upon the slide, a bearing block upon the plate, a rock shaft journaled in the block, a forwardly projecting crank upon one end of the shaft, a downwardly directed needle upon the crank, a forwardly directed stop arm upon the other end of the shaft engageable with the plate, an upwardly directed contact lever upon the stop arm, a horizontal arm supported by the block, and a spring arm carried by the arm 100 engaging and depressing the stop arm.

7. In a device of the type set forth, a loom temple slide, a plate upon the slide, a split bearing block upon the plate comprising a seat section provided with a threaded recess, and a removable section provided with a hole registering with the recess, each section being provided with a semicircular bore and each bore registering with the other, a screw in the hole entering the recess, a rock shaft journaled in the bores of the block sections, a forwardly directed crank arm upon one end of the shaft, a needle upon the crank, an upwardly directed contact lever connected with the other end of the lever, and means for actuating the shaft.

In testimony whereof we have affixed our signatures.

ABRAHAM J. GAOUETTE.
EDWARD J. COTE.
